CENTRIFUGAL GRINDING MILL WITH ABRASIVE LINER AND ANGULARLY DISPOSED FEED CONDUIT

Heinrich Arnold Noll, Duesseldorf, Germany, assignor to H. H. and H. Manufacturing Co., Chicago, Ill., a corporation of Illinois

Application October 7, 1950, Serial No. 189,010
In Germany February 13, 1950

1 Claim. (Cl. 241—86)

1
The invention relates to centrifugal grinding mills or hammer mills and the like employed for grinding or pulverizing ores, coal, grain and other materials including those of a fibrous nature such as wood, and the features of the invention and the principles involved may be embodied in home utility devices such as garbage disposal machines as well as devices for various industrial purposes. In a more particular sense the invention is concerned with a special attrition or grinding surface and effective and efficient processing of materials to be ground or reduced to a pulverized state through the medium of certain special constructions.

Centrifugal or hammer mill grinders perform their functions largely by impact between the rotor elements, (blades or hammers) and the pieces or particles of material to be reduced to smaller pieces or particle size and partly by impact of the pieces or particles against the inside surfaces of the housing or body of the mill forming the grinding chamber, the pieces or particles being batted against the interior wall surfaces of the grinding chamber under high velocities imparted by the whirling vanes, blades or hammers, thereby to be shattered or broken. Of course there is interparticle or piece impact and attrition and a certain amount of grinding occurs through frictional interengagement of the pieces or particles with the grinding chamber walls as those pieces or particles are whirled or batted about in the grinding chamber. Frictional contact of the pieces and particles with the grinding chamber walls also results in grinding away the walls themselves and such wear and tear upon the walls is often very great indeed causing breakdowns and frequent shutdowns for repair and replacement of the worn or otherwise affected parts. The expense of repair and replacement is very high indeed in some mills of this type depending on the material being ground, the material of which the chamber walls are composed and other factors as is well known.

Many attempts have been made to eliminate such wear or to minimize it as well as to improve the effectiveness and efficiency of the grinding action, by employing very hard and tough metal for the chamber walls or by surfacing such walls with very hard material. Other expedients with the same end in view have been adopted. Some of these attempts have been partially successful at least to the extent of extending the useful life of the parts which otherwise would be affected, but generally speaking, most attempts have met

with relatively indifferent success. In some cases, pins, ridges, beating bars, concussion discs and the like projecting from the chamber surfaces into the paths of travel of the material to be ground, have been employed but such constructions are generally costly both initially and on replacement and are otherwise objectionable.

There are also those types of concussion or grinding mills in which the rotor blades, hammers or discs are equipped with friction surfaces or the like for special purposes such as shredding wood or other fibrous material. However, such machines are generally unsuitable for grinding or pulverizing materials such as coal or grain and the like, such materials usually having to be reduced to a powder-like constituency or condition under impact and centrifugal forces which, ordinarily, are not utilized or only utilized to a relatively small extent in pulpy or fibrous material grinding machines. Pulverization is seldom possible in such machines.

It is also desirable, in machines for pulverizing substances, to have the pulverized material i.e., the material which has been reduced to the desired particle size or proper degree of pulverization, removed practically as fast as it has been reduced to such state and to that end mills of the grinding type as distinguished from the shredding type, may be equipped with screens or grates designed to pass the adequately ground fines, as they are formed, from the grinding chamber. Such an arrangement may serve to facilitate reduction of the remaining unpulverized pieces and particles in the grinding chamber and may also permit a more or less continuous flow of material to feed into, through and from the machine. In centrifugal or hammer types of grinding mills, the whirling hammers or blades may serve to aid in blowing or forcing the ground material through a screen or grate into the discharge from the machine. Machines such as those employing rotating friction surfaces for shredding or tearing material, ordinarily do not have grates or screens through which the product is discharged so do not need to have any "fan" action and such machines are generally of the "batch" type as distinguished from the continuous flow type with which the invention is primarily concerned.

Among the principal objects of the invention therefore, is that of providing a centrifugal hammer mill type of grinding machine with a renewable or replaceable lining composed of a relatively hard abrasive substance such as silicon

carbide or aluminum oxide (emery) or the like, such lining being composed, in a preferred form, of a plurality of individual blocks of such abrasive in a sintered or cemented grit or grain size appropriate to the material to be pulverized or ground and being secured or supported by or within the grinding chamber walls in any suitable manner, thereby to provide an effective grinding and abrading surface against which the pieces and particles of material may strike and be abraded and ground under impact and other activating forces induced by the blades or hammers rotating within the chamber.

Another principal object is to provide an arrangement whereby a grinding mill of the character indicated may be utilized for a continuous flow of material in feed, in grinding and in discharging or, for "batch" or intermittent feed, grind and discharge, as may be desired. By reason of the high effectiveness and efficiency of a grinding machine of the character indicated when constructed with abrasive linings of the character mentioned and because an accumulation of pulverized product within the grinding chamber would tend to decrease such effectiveness and efficiency, it becomes highly desirable, under certain circumstances and when grinding or disintegrating certain materials or substances, to remove the disintegrated or pulverized product substantially as fast as it is formed and it is for that reason that the invention in a preferred application features an arrangement permitting such processing.

Many other objects including the novel processing indicated above, as well as the advantages and uses of the invention will be appreciated and understood by those skilled in the art, after reading the following description and claim and after viewing the drawings in which:

Figure 1 is a side elevation, partly in section, of a presently preferred embodiment of the invention, showing a centrifugal or hammer mill, motor drive and impeller shaft mounting;

Figure 2 is a sectional view in end elevation, taken substantially along the section line 2—2 of Figure 1; and

Figure 3 is a detail view of a bottom portion of the mill casing looking at the same from a position to the left of Figure 1.

The mill illustrated in the drawings has been more or less conventionalized and generally comprises a cylindrical casing the ends of which may be closed by end plates 5 and 6, plate 5 being provided with an opening for connection of a supply pipe or chute 7 and also with a bottom opening closed by a plate 8 for purposes to be described, while end plate 6 is provided with an opening surrounded by a stuffing box 9 through which the impeller shaft 11 of the mill passes into the grinding chamber. The shaft 11 is mounted in bearing blocks 12 supported on a bed 13, is driven by a motor 14 through a coupling 15 and, within the grinding chamber, carries a plurality of firmly secured blades or impellers 16, 16', 16'' and 16''''. The axes of the shaft and grinding chamber are coincident or substantially coincident. Attached to the outer ends of the blades or impellers 16, 16' etc. are beaters; plates or hammers 17, which may be formed of any of the usual hard materials employed in mills of this character. The construction of the blades or impellers 16, 16' etc. as well as the type and character of hammers and the other details of construction may be according to any of the usual practices in this art. While

the plates or hammers 17 are shown as connected to each of three aligned blades or impellers it may be preferred to have a separate hammer or plate for each blade or impeller.

The casing of the mill is suitably supported upon a floor or other supporting structure and is provided with an opening at its bottom side leading to a discharge conduit 18 in turn leading to any place of disposal of the pulverized or ground product. Within the casing over the opening leading to the discharge conduit 18 and held in position thereover by any suitable means, is a removable and replaceable screen 19, this being removable through the opening in the bottom of the casing when the cover plate 8 is removed. The details of construction and arrangement of the screen or grate 19 need not be mentioned here since anyone skilled in the art may supply the same. Preferably the screen or grate 19 is arcuate and concentric with the paths of rotation of the blades or impellers and the hammers 17. Preferably also, the feed pipe or conduit 7 is disposed so as to feed the material to be ground into the grinding chamber at a tangent and against the direction of rotation of the impellers so that the impellers tend to pick up the material to be ground and start it in motion before the material can flow onto the grate or screen at the bottom.

Extending from one side of the bottom or discharge opening in the casing entirely around the inside cylindrical face of the grinding chamber to the opposite side of such discharge opening is a lining generally designated 21 and in this instance composed of a series of individual blocks, bars, slabs or bricks 22 of an abrasive substance such as silicon carbide or anhydrous aluminum oxide. This abrasive lining may be fastened directly to the inner surface of the cylindrical wall 4 or it may be secured in any suitable manner to a generally cylindrical metal liner 23 as shown in drawings hereof, the liner 23 and the abrasive lining 22 being assembled from without the casing and inserted and fitted within the casing from either side when an end wall 5 or 6, as the case may be, is removed therefrom. The means by which the lining, whether composed of individual bricks or slabs or as more or less one piece structures, is secured to the inner face of the chamber or to the liner 23 is not here material since any method and means commonly employed to secure abrasive blocks or slabs or furnace lining bricks to their supporting structures may be used as will be understood by those skilled in the art. If it is desired, the end cover plates 5 and 6 may also be lined with an abrasive either in one piece linings or through the employment of individual abrasive blocks or slabs as will also be understood.

As the shaft and the blades or impellers and hammers are rotated at high speed, the material to be ground is fed down the chute or feed conduit 7 and entering the grinding chamber is struck by the plates or hammers 17 and the blades or impellers 16, 16', etc. and broken and thrown continuously against the friction surfaces presented by the abrasive linings. Impact blows struck by the whirling parts and by the forceful striking of the lining of the casing by the pieces and particles as they are batted around within the grinding chamber under centrifugal and other forces, quickly reduces the material to a pulverulent condition and the fines, falling upon the screen or grate 19 fall therethrough under the influence of gravity accelerated by the

fanning or blower effect of the whirling parts. The pieces and particles of material being ground are thrown against the abrasive lining under high centrifugal and rotational forces which serve to abrade and grind the material to the desired size in a very much shorter time and at a lesser expense for power than any prior machine of which I am aware.

The mill of this invention does not operate after the manner of the usual "grinding" and "crushing" mills which are largely dependent upon "dragging," "shearing" and more or less direct "crushing" forces to effect disintegration of the material to be broken or pulverized. Instead, this mill effects disintegration and pulverization by throwing the material to be ground, forcefully, again and again, against and along the abrasive surface lining the grinding chamber so that the material is abraded or "scratched" to pieces by engagement with the hard rasping surface provided by the abrasive. The vanes or impellers whirl the material mass at sufficient velocity to cause those of its particles which are moved to the mass periphery along the abrasive surface to impinge more or less tangentially upon the abrasive surface and the momentum and inertia of the material pieces or particles cause those pieces or particles to contact a substantial number of abrasive particles in the resultant paths of movement of the material in motion over the abrasive surface, breaking or pulverizing the material by frictional attrition. While there is some breakage and pulverization under impact of the impellers against the material and under impact of the material against the abrasive when whirled thereagainst under high velocity, the impellers do not "drag" the material between them and the abrasive surface in a "shearing" or "tearing" sense nor yet is there a "crushing" effect after the manner of a jaw-crusher or stamp mill.

Test and experience results have shown that a grinding mill of the instant type has a high efficiency per unit of power and is effective to secure a desired degree of pulverization in far less time than may be obtained with other types mentioned. However, effectiveness as well as maximum efficiency of functioning requires an optimum relationship between the quantity discharged and the quantity ground per unit of time. That optimum relationship is a function of several factors but, other factors being equal or controlled, the proportion of total abrasive surface area to the area of the screened discharge opening is, perhaps, the most important. It has been found by tests and experiments mentioned above that the abrasive area of a cylindrical abrasive surface in a machine of the type disclosed herein should be substantially greater than one-half of the total cylindrical surface area and, preferably, greater than two-thirds of the total and up to approximately five-sixths of such total as indicated (by proportion) in the drawing. On the other hand the discharge of ground material must be sufficient to prevent inefficiency due to clogging and yet must not be so rapid as to reduce the grinding efficiency, but optimum conditions may be obtained, where the screened discharge is under gravity flow plus the blowing effect of the whirling impellers is available, when the screened discharge area is at or between approximately one-fifth and one-third of the total internal cylindrical surface area. In Fig. 2, the screened discharge length in a circumferential direction is illustrated as being

somewhat less than one-fifth or approximately one-sixth of the total circumference internally of the machine.

Properly chosen and constructed, abrasive linings of the character indicated will last over a long period of time and are remarkably effective and efficient in grinding very hard materials such as ores as well as relatively soft material such as grain. When a lining is worn to a state where its efficiency or usefulness is impaired, it may be removed and replaced with a new lining but by utilizing linings of the types mentioned the grinding efficiency and effectiveness remain substantially constant until the linings are completely worn away. When a screen or grate plate is worn or damaged in use, it may be removed and replaced with ease.

The mill constructed after the manner described is effectively cooled and the material ground therein is maintained at a satisfactory low temperature especially when the material is continuously being fed and the ground material is continuously being discharged and through the "fan" action effected by the rotating parts. The mill is simple in construction, its cost of repair and maintenance is small and it produces a ground product of uniform fineness quickly and efficiently. Obviously, the features may be embodied in other forms.

While I have illustrated and described my invention in its presently preferred form, many changes as well as modifications may be made therein without departing from the invention spirit and the scope of the appended claim.

I claim:

In a material grinding machine, a horizontal casing having a cylindrical internal wall, end walls for said casing providing a chamber for the reception of material to be ground, a rotatable shaft projecting into said chamber on an axis co-axial with said chamber axis through one end wall and terminating in the chamber to form an end and the opposite end wall being formed with an opening for feeding material into the casing, said chamber being provided with an outlet opening formed in the lower portion of the cylindrical wall thereof, the area of said opening being not substantially greater than one-sixth of the internal wall area of the horizontal casing, screen means disposed over said opening and conforming in contour to the cylindrical internal wall of said casing, said cylindrical wall being provided with a removable liner having an internal surface of abrasive material, said liner extending circumferentially within the cylindrical casing from one edge of said screened opening to the other and from one end wall to the other end wall, radially extending arms carried by said shaft, material impelling blades carried by said arms, and a feed conduit at one end of the casing extending downwardly and inwardly with its lower end disposed centrally and presented to the end of the rotary shaft for feeding material to the chamber through said opening in the end wall, said feed conduit being angularly displaced with respect to a vertical plane passing through the axis of the shaft and about said shaft in the same direction of rotation thereof a sufficient distance to feed material to the abrasive surface of said liner in advance of the screen means.
